UNITED STATES PATENT OFFICE

2,676,628

POLE PEELER ATTACHMENT FOR PORTABLE
CHAIN SAWS

Charles S. Hastain, North Bonneville, Wash.

Application June 12, 1952, Serial No. 293,040

6 Claims. (Cl. 144—208)

1

The present invention relates to tools for debarking or trimming logs or posts and more particularly relates to a log trimming tool attachment for use with a portable power-driven chain saw.

The primary object of the present invention is to provide a log trimming tool attachment that may be quickly and simply attached to the motor housing of a portable chain saw whereby the log trimming tool or pole peeler may be driven by the chain saw motor.

A further object of the invention ancillary to the preceding object is to provide a log trimming attachment whereby the log trimming tool is reciprocated by the chain saw motor for expeditiously trimming logs or posts.

A still further object of the present invention is to provide a power driven log trimming attachment wherein the log trimming tool is guided for reciprocation in a novel manner.

Still further features of the present invention reside in its simplicity of construction, efficiency in operation, durability and the ease with which the attachment may be mounted on a portable chain saw motor housing.

These, together with various ancillary features and objects which will later become apparent as the following description proceeds, are attained by this invention, a preferred embodiment of which is shown by way of illustration only in the accompanying drawings, wherein:

Figure 1 is a perspective view of the log trimming attachment of the present invention mounted on the motor housing of a portable chain saw and being shown in operative position;

Figure 2 is a top view of the attachment with parts of the log trimming tool being broken away;

Figure 3 is a side view of the attachment also with parts of the log trimming tool being broken away;

Figure 4 is a side view of the attachment along section line 4—4 of Figure 2 showing the novel guide means whereby the log trimming tool is reciprocated;

Figure 5 is a sectional view taken substantially along section line 5—5 of Figure 4 showing the operating means whereby the log trimming tool may be reciprocated; and

Figure 6 is a perspective view of the log trimming tool per se.

Referring now more specifically to the accompanying drawings wherein like numerals designate like parts throughout the various views, attention is first directed to Figures 2—6 wherein the details of the attachment are most clearly shown.

2

The attachment in its entirety is designated generally by the numeral 10 and comprises generally an attaching or mounting plate 12, log trimming tool 14, guide means 16 and driving means 18.

The mounting or attaching member 12 comprises a generally flat, rectangular shaped plate being rounded at one end as at 20 and having tapered side edges 22 and 24 tapering from an intermediate portion thereof toward the other end 26, the corners of which are likewise rounded. An elongated slot 28 extends for a portion of the length of the attaching plate 12 intermediate the tapering side edges 22 and 24 and opens into end 26. The function of this open end slot 28 is to facilitate mounting or attaching the plate 12 to the motor housing of a portable chain saw in a manner that will later become apparent.

Secured to one face or surface of the attaching plate 12 centrally thereof are a pair of spaced, parallel bars 30 and 32 having one pair of ends thereof interconnected by a web 34. The bars 30 and 32 and the web 34 are fixedly secured to the surface of the plate 12 in any conventional manner throughout their length with the bars 30 and 32 being in parallel relation to the side edges of the plate 12 and having their free ends 36 and 38 terminating coextensively with rounded end 20. Each of the bars 30 and 32 have arcuate recesses therein designated by the numerals 40 and 42, respectively, in opposed relation to each other on their facing surfaces. As shown in the preferred embodiment, the bars 30, 32 and the web 34 are integral with one another and form a deep flanged channel or U-shaped element.

A cam shaft 44 of the driving means 18 extends transversely through an aperture 45 in the attaching plate 12 and is rotatably journaled therein. One end of the cam shaft 44 projects between the bars 30 and 32 medially of the arcuate recesses 40 and 42. Fixedly mounted on this portion of the shaft 44 by a key 46 is a disk 48. The disk 48 is mounted eccentrically on the shaft 44 and comprises the cam for the cam shaft 44. With specific reference to Figure 4, it will be seen that this eccentrically mounted disk 48 rides between the arcuate recesses 40 and 42 of the bars 30 and 32, respectively. Fixedly keyed to the other end of the shaft which is disposed on the other side of the mounting plate 12 is a pulley 50 which may be keyed on the shaft, although not shown, in the same manner as the disk 48. To space the pulley 50 from the surface of the plate 12 a spacing washer 52, which may be in the form of a conventional bearing, is mounted. A set screw 54 extending through a hub 56 of the pulley 50

frictionally abuts the cam shaft 44 to prevent sliding movement of the pulley with respect to the shaft. Thus, it will be seen that driving means 18 comprises pulley 50, shaft 44 and cam 48.

Spaced, threaded bores 58 are provided in the surfaces of bars 30 and 32 and web 34 opposite the attaching surfaces of these members to plate 12. A rectangular closure plate 60 is mounted on the surfaces of the bars 30, 32 and the web 34 and fasteners 62 extend through this closure plate and are threadedly received in the apertures 58 to secure the plate to the bars and web. By means of this construction, a longitudinal, open end recess 64 opening at the end 20 of the mounting plate 12 is formed. Thus, plate 60, bars 30, 32, web 34 and that portion of the surface of plate 12 between the bars and web define the guide means 16 for the log trimming tool 14.

Disposed within the longitudinal recess 64 is a shank 66 of the log trimming tool 14. To maintain the end of the tool shank 66 in abutting engagement with the cam 48, closure plate 60 is provided with a longitudinal slot 68 which corresponds in length approximately to twice the radial distance between the true center of disk 68 and the eccentric mounting of this disk. A threaded bore 72 is provided in the tool shaft in alignment with the slot 68 and a screw threaded fastener 70 extends through the slot 68 and is threadedly received in the bore 72 of the shank 66 thereby permitting reciprocal movement of the tool shank 66 within the longitudinal recess 64.

To maintain the end of the tool shank 66 in engagement with the eccentrically mounted disk 48, a resilient means 74 is provided in the form of a coil spring. One end of the coil spring 74 is secured to the fastener 62 extending into the web 34 while the other end of spring 74 is secured to the fastener 70, thereby constantly biasing the end of the tool shank 66 into abutting engagement with the cam 48 whereby rotation of the cam shaft 44 will cause reciprocation of the tool shank 66. Secured to the other end of the tool shank 66 is a log trimming blade 76 having a cutting edge 78 thereon. Upon reciprocation of the tool shank 66, the blade 76 exerts a highly advantageous chipping action that removes bark from trees or posts in an extremely efficient manner.

Referring now to Fig. 1 of the drawings, the mounting and operation of the attachment in a bark stripping operation can be clearly observed. Shown in this figure is a conventional portable, power-driven chain saw designated generally by the numeral 80, the housing of which has a forwardly extending vertical wall 82 thereon. Horizontally spaced studs 84 project laterally from the wall 82 and these studs are received between the edges of slot 28 in attaching plate 12. To maintain the attaching plate 12 rigidly upon the wall 82, a pressure plate 86 is disposed on the studs 84 so that the plate 12 is confined between this pressure plate and the side wall 82. Nuts 88 are threaded onto the studs 84 and frictionally retain the plate 12 between the pressure plate 86 and the chain saw housing side wall 82. A pulley 90 adapted to be driven by the motor (not shown) of the portable chain saw 80 is mounted on the housing of the chain saw 80 and a V-belt 92 interconnects the pulley 50 of the attachment 14 with the pulley 90. Thus, upon actuation of the pulley 90 rotation of pulley 50 will result thereby causing the tool shank 66 of the tool 14 to reciprocate within the guide means 16 of the

log trimming attachment and thereby effectively chip the bark from a log or post as indicated at 94.

In view of the simplicity of the attachment, further description is believed to be unnecessary. However, since numerous modifications in the construction and arrangement of the device will readily occur to those skilled in the art after a consideration of the foregoing specification and the accompanying drawings, applicant does not intend to be limited to the exact construction shown and described but may resort to any changes and modifications that fall within the scope of the appended claims.

Having described the invention, what is claimed as new is:

1. A log trimming attachment for use with a portable chain saw motor housing, said attachment comprising a mounting plate adapted to be secured to the chain saw motor housing, guide means mounted on said mounting plate, a log trimming tool carried by said guide means for reciprocating movement therein, driving means on said mounting plate adapted to be operatively connected to the chain saw motor, cam means interconnecting said driving means and said tool for reciprocably moving said tool, and resilient means maintaining said tool in abutting engagement with said cam means.

2. The combination of claim 1 wherein said guide means includes a housing having a longitudinal recess therein, said tool having a portion thereof slidably disposed in said recess.

3. The combination of claim 1 wherein said guide means includes a housing having a longitudinal recess therein, said tool having a portion thereof slidably disposed in said recess, said housing comprising a U-shaped member secured along one side thereof to said mounting plate and having a detachable closure plate mounted on the other side thereof.

4. The combination of claim 1 wherein said mounting plate has an elongated slot opening at one edge thereof for securing the same to the chain saw motor housing.

5. A log trimming attachment adapted to be mounted on a portable chain saw motor housing, said attachment comprising a flat mounting plate, a shaft journaled transversely through said plate, guide means adjacent said shaft secured to one side of said mounting plate, a disk eccentrically mounted on said shaft adjacent said guide means, a tool shank slidably received in said guide means and having one end in abutting engagement with said disk, a pulley on said shaft adapted to drivingly rotate the shaft, resilient means maintaining said tool shank in abutting engagement with the disk upon rotation of the shaft, and a cutter blade carried by said tool shank.

6. A log trimming attachment comprising an attaching plate, guide means mounted on said plate, a log trimming tool slidably received in said guide means, cam means rotatably mounted on said attaching plate and means operatively connecting said cam means to said tool, said tool being reciprocably slidable in said guide means upon rotation of said cam means, said guide means including a pair of spaced elongated members secured in parallel relation to one another on said plate, and a removable closure plate being secured to said bars in spaced parallel relation to said attaching plate, said closure plate having a longitudinally disposed slot therein, said tool having a pin extending through said slot,

2,676,628

5

and resilient means interconnecting said pin and said closure plate to bias the pin toward one end of the slot.
